Attorney

UNITED STATES PATENT OFFICE.

WARREN C. DICKERSON, OF LOS ANGELES, CALIFORNIA.

WIRE-STRETCHER.

1,237,875.

Specification of Letters Patent. Patented Aug. 21, 1917.

Application filed January 2, 1917. Serial No. 140,146.

To all whom it may concern:

Be it known that I, WARREN C. DICKERSON, a citizen of the United States, residing at Los Angeles, in the county of Los Angeles and State of California, have invented certain new and useful Improvements in Wire-Stretchers, of which the following is a specification.

My invention relates to certain new and useful improvements in tools or implements designed for the stretching of wire upon screen frames, for covering window and door openings to prevent the admission of flies and other insects.

15 A leading object of my invention is to provide a device such as referred to, which consists of few parts and is, therefore, simple in construction and may be cheaply manufactured, and which has one part to engage the meshes of the wire and another part to fulcrum against and slide over the outer edge of the frame to which the wire is to be attached, to thereby stretch the wire and to lock against the frame and maintain 25 itself in place with the wire under tension during the subsequent tacking of the wire to the frame.

With the above and other objects in view my invention consists of the parts and the 30 constructions, arrangements and combinations of parts, which I will hereinafter describe and claim.

In the accompanying drawing forming part of this specification and in which similar letters of reference indicate like parts in the several views;

Figure 1 is a perspective view of a portion of a window or door-screen showing the stretcher in its initial engagement with 40 the wire sheet.

Fig. 2 is a similar view showing the stretcher locked in position on the frame and holding the wire in its stretched or tightened condition.

45 Fig. 3 is a cross sectional view on the line 3-3 of Fig. 2.

Fig. 4 is a perspective view of the slideable jaw.

Fig. 5 is a longitudinal sectional view of 50 a device of modified form.

Fig. 6 is a bottom plan view of Fig. 5 showing parts broken away.

In carrying out my invention I employ a body-portion, A, and which I will herein-

after refer to as a stationary jaw, said jaw being of sufficient length to enable one part of it to pass over the ordinary window or door stile or rail, for a sufficient distance to engage the sheet of screen-wire, which ordinarily is laid thereon, said jaw having its shank, A', extending rearwardly a sufficient distance beyond the frame to serve as a handle by which the tool or implement may be manipulated. The forward edge of this stationary jaw, A, is turned to one side and is serrated to form a series of teeth, a, which are designed to enter between the meshes of the wire-cloth and to take secure hold of the same.

Slidably mounted upon the stationary jaw is an arched clamping yoke or frame, B, the side members of which are turned under the side edges of the jaw, A, to form guides or channels, e, thereby enabling the yoke or frame to be adjusted back and forth on the stationary jaw, said inturned ends of these sides also serving to receive and to hold the slideable jaw, C, of the device. The slideable jaw consists of a bent plate or bar having one part, 2, arranged parallel to the shank of the stationary jaw, A, and having another part, 3, substantially at right-angles to the first-named part and to the shank of the stationary jaw and adapted to extend down over the outer edge of the stile or rail of the screen-frame and to bear with increasing pressure thereon, whereby the stationary jaw is drawn outwardly and the screen-wire engaged thereby is stretched or placed under tension, as the device is moved from the position shown in Fig. 1, to the locked position shown in Fig. 2, in which latter position it will be found that the device becomes locked to the frame and cannot be displaced except by force applied in a reverse direction to the outer shank portion of said stationary jaw. When in this aforesaid locked position, the wire is held tightly stretched over the frame, in which position it may be tacked in the usual manner, after which the device may be released and applied to another portion of the wire and operated as before described.

In order that the movable jaw, C, of the device may be adjusted relatively to the toothed or gripping end of the opposed jaw, A, and may then be rigidly or immovably locked to the latter, I may locate under the

arched portion of the clamp, or yoke, B, a plate or nut, E, which is confined between the shank of the stationary jaw, A, and the under surface of the yoke or clamp and has 5 a threaded opening adapted to receive the corresponding portion of a thumb-screw, F, wing-nut or the like, the end of which is designed to bear against the shank, A', so that when the screw is turned the nut or plate 10 will be caused to ride thereon and to bear against the inner surface of the yoke and thereby cause the clamp and the movable jaw member carried thereby to be tightly clamped against and held to the shank of the stationary jaw.

To prevent the detachment of the slideable jaw from its associated clamp, if desired, any well-known means may be employed.

In Figs. 3 and 4 suitable lugs, 4, are 20 shown as being formed on the edges near one end of the bent slideable jaw and the outer ends of the inturned portions of the sides of the yoke or clamp are engaged by these lugs to lock the clamp to said jaw member 25 and thus prevent the detachment of these parts.

In applying the device, the toothed end of the stationary jaw is first engaged with the meshes of the wire cloth, as shown in Fig. 30 1. The clamp is then released and pushed inward until the out-turned portion of the movable jaw comes against the edge of the stile or rail of the frame to which the wire is to be attached and then the clamp is 35 secured immovably in place. The operator then presses upon the shank of the stationary jaw and as the bent outstanding portion of the slideable jaw rides over the edge of the screen-frame, it serves as a fulcrum 40 and causes the device to move outwardly with the result that the wire is tightly stretched. When the shank, A', has been pressed down upon or in contact with the screen-frame, the device will be so locked 45 to said frame that it will retain itself in this position to thereby enable the operator to use both hands in tacking or nailing the wire cloth to the frame.

The device shown in Fig. 5 is similar in 50 construction and operation to the one shown in Figs. 1 and 2, and before described, except that the form of clamp is slightly different. In this case the stationary jaw, H, is slotted longitudinally as shown at 10 55 and the slideable jaw, I, is formed with a tongue, 11, which operates in said slot, and guides the jaw in its movements. A bolt, 12, having a head on its underside passes upwardly through the slideable jaw and the 60 slot in the body of the stationary jaw and through a washer, 13, and has its upper portion engaged by a wing-nut, 14. In the modified form of device shown in Figs. 5 and 6, I also employ a lever, 15, the inner 65 end of which is mounted on the aforesaid

bolt and has a cam-portion, 16, the purpose of which I will now describe. Assuming that the device of Fig. 1 has been engaged with the wire-cloth and screen-frame in the manner before described, and has been 70 pressed into the locked position shown in Fig. 2, and it is desired to further stretch the wire while the device is in this locked position, the lever, 15, which we will assume is open and is projecting laterally, may 75 now be closed or turned about the bolt as a pivot and as its cam-portion, 16, rides in contact with the inner face of the out-turned portion of the movable jaw, which now fulcrums tightly against the edge of the screen-frame, the stationary jaw, A, which is in engagement with the wire will be caused to move outwardly for a further distance thereby 80 more tightly stretching the wire, said lever becoming locked after passing the dead center and remaining in this position until it is desired to release the parts which may be done by moving the lever in a reverse direction from that before described, as will be well understood by those skilled in the 85 art.

The out-turned portion of the movable jaw may be substantially straight as in Fig. 1, or it may be slightly curved as in Fig. 5 without departing from the spirit of my invention, this portion in either case serving as 95 the fulcrum about which the device may be moved in applying it to the screen-frame or releasing it therefrom.

Having thus described my invention what 100 I claim as new and desire to secure by Letters Patent is:—

1. In a fabric stretching device, the combination of a relatively thin, wide, flat jaw having a shank portion, said jaw having a 105 row of teeth projecting substantially at right-angles thereto for engaging the fabric to be stretched, a jaw co-acting with the first-named jaw and slidably mounted thereon and bent to form two members one of 110 which is substantially parallel to said shank and the other is substantially at right-angles to the shank, and is adapted to fulcrum against the edge of a frame to which the fabric is to be applied, and means for clamping 115 said second jaw rigidly to said shank.

2. In a fabric stretching device, the combination of a relatively thin, wide, flat jaw having a shank portion, said jaw having a row of teeth projecting substantially at right-angles thereto for engaging the fabric to be stretched, a jaw co-acting with the first-named jaw and slidably mounted thereon and bent to form two members one of which is substantially parallel to said shank and the other is substantially at right-angles to the shank, and is adapted to fulcrum against the edge of a frame to which the fabric is to be applied, and means for clamping 125 said second jaw rigidly to said shank, said clamp- 130

ing means comprising a yoke having side portions straddling the edges of said shank and overlapping the edges of the adjustable jaw and forming a guide for adjusting one 5 jaw relatively to the other.

3. In a fabric stretching device, the combination of a jaw having a shank portion and means for engaging the fabric to be stretched, a jaw co-acting with the first- 10 named jaw and slidably mounted thereon and bent to form two members one of which is substantially parallel to said shank and the other is substantially at right-angles to the shank, and is adapted to fulcrum against 15 the edge of a frame to which the fabric is to be applied, means for clamping said second jaw rigidly to said shank, said clamping means comprising a yoke having side portions straddling the edges of said shank 20 and overlapping the edges of the adjustable jaw and forming a guide for adjusting one

jaw relatively to the other, a nut within the yoke and a screw engaging said nut.

4. In a fabric stretching device, the combination of a jaw having a shank portion, 25 said jaw extending continuously substantially in line with the shank and having its outer end provided with a row of teeth which project substantially at right angles to the jaw and shank, said teeth adapted to 30 engage the fabric to be stretched, and a jaw carried by said shank portion and bent to form two members one of which extends along parallel to the shank and the other is arranged substantially at right angles to 35 said shank and is adapted to fulcrum against the edge of a frame to which the fabric is to be applied, said last-named member being relatively wide to form a broad bearing against the edge of said frame. 40

In testimony whereof I affix my signature.

WARREN C. DICKERSON.
